UNITED STATES PATENT OFFICE.

WILLIAM A. EDWARDS, OF CHICAGO, ILLINOIS.

DASHPOT-CONTROLLED AIR VALVE FOR INTERNAL-COMBUSTION ENGINES.

Application filed September 18, 1923. Serial No. 362,583.

To all whom it may concern:

Be it known that I, WILLIAM A. EDWARDS, a citizen of the United States, having residence at Chicago, in the county of Cook and State of Illinois, have invented certain new and useful Improvements in Dashpot-Controlled Air Valves for Internal-Combustion Engines, of which the following is a specification, reference being had to the accompanying drawings, forming a part thereof.

The purpose of this invention is to provide an improved construction of yieldingly-seated valve, adapted to be opened by the suction of an engine for admitting air for the fuel mixture. It consists in the elements and features of construction shown and described, as indicated in the claims.

The drawing is a sectional elevation of the fuel mixture conduit including fuel connections leading from the supply tank.

In the drawings the feature constituting this invention is shown applied to a fuel mixture conduit of the character and arranged in relation to the engine and fuel supply tank, in accordance with the invention shown in my Patent No. 1,437,048, dated November 28, 1922, but it should be understood that the present invention is not limited to use in conjunction with such an air conduit or in the particular situation relatively to the air conduit and the mixing devices which it sustains when associated with the particular air conduit and mixer of my said patent; but, on the contrary, it is designed and adapted to be applied to and co-operate with any air conduit for supplying air for the fuel mixture in an internal combustion engine or any like situation.

In the drawings A represents the main fuel tank; B the air conduit leading to the engine intake indicated at C. D is the fuel conduit discharging in the air conduit for intermixture of the liquid fuel and air. In the particular construction shown there is a limited air inlet at c for admixture of a limited quantity of air with the fuel delivered in the venturi, C¹, in which the fuel nozzle, d, discharges. The main air supply, however, for the fuel mixture is admitted past the valve, E, which is normally held yieldingly seated by the springs, F, and adapted to be opened by the engine suction for taking in the air and fuel charge. In the absence of provisions to the contrary, a

spring-seated air intake valve such as thus far described, is liable to be opened excessively by the sudden access of suction, by reason of the inertia of the valve which upon being pulled from its seat by the sudden suction, tends to compress the spring by which it is seated to a greater degree than the degree of suction, if applied gradually, would be able to compress the spring; and for this reason when the engine is operating at high speed causing the suction to operate with a sudden pull upon the valve, the valve is opened more widely than it would be opened by the same suction, if the engine were running more slowly. This variation in air access for the fuel mixture, disproportionate to the air requirements at the different engine speeds, it is the purpose of this invention to prevent. For this purpose the spring-seated air valve is connected with a dash-pot device which retards the opening movement, tending to conserve the force of the suction by which the opening of the valve is caused and prevent the inertia of the valve from causing it to be opened except in strict accordance with the degree of the suction. The construction for this purpose will now be described in detail.

The valve, E, is a piston slide valve cylindrical in form and obtaining its slide seat in a sleeve, G, suspended or carried by its upper end from the upper end of the cylindrical housing member, H, whose open lower end is connected for opening into the air conduit, B. At the lower open end of the housing, H, there is mounted a spider, H¹, which at h, affords a guide bearing at its center for the stem, E¹, of the valve, E. The spring, F, coiled around the stem, E¹, reacts at its upper end against the head of the piston valve, E, and at the lower end against the spider mentioned, tending to uphold the valve to the position shown in full line in the drawing at which the said valve is seated, closing the ports, g, g, in the cylindrical seat, G, and thereby adapted to uncover said ports proportionately to the sliding movement of the valve against the yielding resistance of the spring. The ports, g, are narrow relatively to the total periphery of the valve,—that is, the extent of the seating of the valve transversely to the direction of its opening movement,—so that in comparison with a disk valve or valve in any form opening at its entire periphery,

the amount of movement which the valve must make for maximum opening is relatively large. As illustrated, the ports, *g*, occupy about one-half the circumference of the valve and its seat. The valve seat, *G*, is, as stated, carried by the upper end of the housing, *H*, but this upper end is not integral with the said housing, but is, in fact, the lower end of the dash pot chamber, *K*, which is cylindrical and has its lower end screwed into the upper end of the housing, *H*, to form the head of the latter. This lower end, *K*¹, of the dash pot chamber has a central opening from whose margin the valve seat, *G*, depends, being conveniently formed integrally with said lower end of the dash pot chamber, *K*. The valve, *E*, has an upwardly-extending stem, *E*², axial with respect to the dash-pot chamber, *K*, and carrying rigidly at its upper end the dash-pot piston member, *K*². The upper end of the dash-pot chamber, *K*, is closed by the screwed-on cap, *K*³.

The dash-pot chamber, *K*, has a multiplicity of lateral apertures, *h*, and is provided with an exterior valve sleeve, *L*, having apertures adapted to register with the apertures, *h*, and intervening areas adapted to close said apertures upon rotation of the valve sleeve for which the handle, *L*¹, is provided.

Upon consideration of the foregoing structure, it will be understood that upon suction operating for retracting the valve, *E*, to uncover the ports, *g*, such movement of the valve will be impeded by the fact that any movement of the valve must be accompanied by equal movement of the piston member, *K*², of the dash-pot, and that such movement of said piston member will produce a vacuum above it in the dash-pot chamber. And it will be understood that the degree of impedance will depend upon the snugness of fit of the piston member, *K*², in the cylindrical dash-pot chamber, and that said movement will be more or less free according to the air leakage past the piston, *K*². A sufficient relief for permitting the necessary or desirable movement of the dash-pot piston is afforded by making said piston for ordinarily close and ordinarily free sliding fit in the cylinder; that is, the air leakage past it will be sufficient when the piston is apparently, to the eye, close fitted. The actual air leakage is exaggerated in the drawings by being shown visible as seen at *h*¹. The piston may be more closely fitted than as above indicated, and leakage provided by such means as a threaded hole through the piston with a loosely fitting screw therein, as seen at *K*⁴. The piston in this case being desirably provided with a boss, through which the threaded hole being made, as seen at *K*⁵, will be of considerable length so that by screwing the

screw, *K*⁴, more or less into and through this boss, the impedance to air leakage may be varied and the device adjusted for the desired degree of retardment of the opening movement of the valve, *E*. It will be understood from the foregoing description and from the drawings that the course of the air admitted past said valve is, in through the apertures, *h*, in the dash-pot chamber wall, thence down through the sleeve valve seat, *G*, and over the top of the valve and out through the apertures, *g*, to the extent to which they are uncovered by the depression of the valve, and thence down outside the sleeve valve seat and past the lower end of the same which stops short of the spider, *H*¹, and out through the open lower end of the fitting, *H*, into the air conduit.

I claim:

1. In a fuel feeding device for internal combustion engines in combination with a conduit through which air for fuel admixture is drawn by the engine suction, a valve controlling atmosphere access to said conduit, a dash-pot device connected with the valve for retarding its opening, the valve being a piston and the slide seat a cylinder having lateral ports; a chamber which encloses said cylinder, the latter being carried by one end of said chamber and terminating short of the other end, said chamber being mounted by said other end on the conduit for communication therewith.

2. In a fuel feeding device for internal combustion engine in combination with a conduit through which air for fuel admixture is drawn by the engine suction, a valve controlling atmosphere access to said conduit, a dash-pot device connected with the valve for retarding its opening, the valve being a piston and the slide seat a cylinder having lateral ports; a chamber which encloses said cylinder, the latter being carried by one end of said chamber and terminating short of the other end, said chamber being mounted by said other end on the conduit for communication therewith, the dash-pot device consisting of a cylinder co-axial with the piston valve closed at one end; a piston reciprocating in said cylinder carried by the piston valve in the opening movement of the latter, said piston being constructed and fitting in said cylinder for limited air leakage past the piston in its stroke with the opening movement of the valve.

3. In a fuel feeding device for internal combustion engine in combination with a conduit through which air for fuel admixture is drawn by the engine suction, a valve controlling atmosphere access to said conduit, a dash-pot device connected with the valve for retarding its opening, the valve being a piston valve and its slide seat a cylinder having lateral ports; a cylindrical chamber which encloses said cylinder, the lat-

ter being carried by one end of said cylindrical chamber and terminating short of the other end, a spider mounted at said other end, and a spring reacting between said 5 spider and the valve, said chamber being adapted at its open end for coupling onto the conduit for atmospheric inlet thereto.

4. In a fuel feeding device for internal combustion engine in combination with a 10 conduit through which air for fuel admixture is drawn by the engine suction, a valve controlling atmosphere access to said conduit, a dash-pot device connected with the valve for retarding its opening, the valve being a piston valve and the slide seat a cylinder having lateral ports, a cylindrical chamber which encloses said cylinder, the latter being carried by one end of said cylindrical chamber and terminating short of the other 15 end, said other end being open and adapted for mounting on the conduit for communication therewith; a second cylindrical chamber, screwed onto the end of the first mentioned cylindrical chamber and forming the 20 head of the latter by which the cylindrical valve seat is carried, the valve having a stem extending axially in said second cylindrical chamber and the piston carried by said stem, said second chamber and piston constituting the dash-pot.

5. In a fuel feeding device for internal combustion engine in combination with a conduit through which air for fuel admixture is drawn by the engine suction, a valve 25 controlling atmosphere access to said conduit, a dash-pot device connected with the valve for retarding its opening, the valve being a piston valve and the slide seat a cylinder having lateral ports, a cylindrical chamber which encloses said cylinder, the latter being carried by one end of said cylindrical chamber and terminating short of the other 30 end, said other end being open and adapted for mounting on the conduit for communication therewith; a second cylindrical chamber, screwed onto the end of the first mentioned cylindrical chamber and forming the head of the latter by which the cylindrical valve seat is carried, the valve having a stem 35 extending axially in said second cylindrical chamber and a piston carried by said stem, said second chamber and piston constituting the dash-pot, said dash-pot chamber having a closure for the upper end and being laterally apertured at a portion of its length, said apertures commencing at a distance from the closed end; whereby the 40 retarding chamber of the dash-pot is formed between said closed end and the proximate ends of said aperture and the apertures afford access for atmosphere to the valve chamber and past the valve to the conduit.

6. In a fuel feeding device for internal

combustion engine in combination with a conduit through which air for fuel admixture is drawn by the engine suction, a valve controlling atmosphere access to said conduit, a dash-pot device connected with the valve for retarding its opening, the valve being a piston valve and the slide seat a cylinder having lateral ports, a cylindrical chamber which encloses said cylinder, the latter being carried by one end of said cylindrical chamber, the latter being at the other end and adapted for mounting on the conduit for communication therewith; a second cylindrical chamber, screwed on to the end of the first mentioned cylindrical chamber and forming the head of the latter by which the cylindrical valve seat is carried, the valve having a stem extending axially in said cylindrical chamber and a piston carried by said stem, said second chamber and piston constituting the dash-pot, said dash-pot having a closure for the upper end and being laterally apertured at a portion of its length, said apertures commencing at a distance from the closed end, and a valve member mounted on the dash-pot for closing said apertures more or less at will.

7. In a fuel feeding device for internal combustion engine in combination with a conduit through which air for fuel admixture is drawn by the engine suction, a valve controlling atmosphere access to said conduit, a dash-pot device connected with the valve for retarding its opening, the valve being a piston valve and the slide seat a cylinder having lateral ports, a cylindrical chamber which encloses said cylinder, the latter being carried by one end of said cylindrical chamber and terminating short of the other end, said other end being open and adapted for mounting on the conduit for communication therewith; a second cylindrical chamber, screwed onto the end of the first mentioned cylindrical chamber and forming the head of the latter by which the cylindrical valve seat is carried, the valve having a stem extending axially in said second cylindrical chamber and a piston carried by said stem, said second chamber and piston constituting the dash-pot, said dash-pot chamber having a closure for the upper end and being laterally apertured at a portion of its length, said apertures commencing at a distance from the closed end; and a sleeve rotatable on the apertured dash-pot wall and apertured for registration of its apertures with the dash-pot apertures and adapted to close the latter more or less by angular adjustment about the dash-pot.

In testimony whereof, I have hereunto set my hand at Chicago, Illinois, this 10th day of September, 1923.

WM. A. EDWARDS.
